BY *Leaseayde* *Victor J. Evans*

WITNESS:

ATTORNEY

UNITED STATES PATENT OFFICE

JOHN A. DOODY, OF TRACY, CALIFORNIA

VEHICLE

Application filed November 1, 1930. Serial No. 492,789.

This invention relates to toy vehicles and more particularly to the wheeled type having the body shaped in animation of an animal or fowl familiar to children.

5 An additional object of the invention consists of a pedal operated steering wheel for the toy.

An additional object of the invention contemplates the provision and arrangement of 10 an operating mechanism for opening and closing the mouth of the figure comprising the body.

An additional object of the invention embodies an annunciator located for simultaneous 15 operation with the opening and closing of the figure's mouth through operation of the operating mechanism whereby the figure will appear to expel natural or life like sounds peculiar to the animal or fowl imitated.

20 With the above and other objects in view, the invention further consists of the following novel features and details of construction, to be hereinafter more fully described, illustrated in the accompanying drawing and 25 pointed out in the appended claim.

In the drawing:

Figure 1 is a longitudinal sectional view taken through the invention.

Figure 2 is a top plan view thereof.

30 Referring to the drawing in detail wherein like characters of reference denote corresponding parts, the reference character 10 indicates generally the body of the figure toy which as shown is a representation of a 35 goose or similar variety of fowl, preferably of hollow construction. A steering shaft 11 projecting through the body of the housing adjacent the base or juncture of association of the goose neck with the body has suitably 40 arranged thereon a stop collar 12 abutting the upper and outer surface of the body to restrict downward motion of the steering shaft beyond a predetermined point.

A wear plate 13 of angular formation is 45 disposed in the manner suggested in Figure 1 of the drawing whereby a flat surface is exposed to the yoke end 14 of a fork member 15. The wear plate 13 and yoke portion 14 are apertured to facilitate protruding of 50 the steering shaft 11 therethrough whereby

the lowermost squared extremity 16 of the shaft may be accommodated within a correspondingly shaped opening 17 in a partition member 18 joined at its ends with the adjacent side walls of the fork arms. A pedal shaft 19, journaled upon and between the fork arms, has fixedly connected thereto between the fork arms a combination power and steering wheel 20. An axle shaft 21 having wheels 22 journaled at the terminals thereof is connected with the rear portion of the body through the arrangement of arms 22'. A saddle or seat 23 having a shaft 24 protruding through a bushing 25 upstanding from the back or upper surface of the figure, projects at its extreme end through the bottom wall of the figure to accommodate a nut or other fastening 26.

55 A handle bar 27 or the like mounted upon the uppermost projecting end of the steering shaft 17 carries grips or other hand engaging portions 28 upon the extremities thereof located within convenient reach of the operator seated upon the saddle 23.

60 As shown in the drawing and as intimated 70 from the foregoing description, the body of the toy is in imitation of a goose or fowl of similar variety having an elongated beak or bill. The lowermost section 29 of the bill is pivotally mounted for rocking motion, as 75 at 30, within the confines of the hollow body at 30, within the confines of the hollow body through the provision and arrangement of apertured ears 31 accommodating a shaft, rivets or the like.

80 The innermost projecting end of the lower 85 bill or beak section is provided with an offset projection 32 telescopically associated with a compression spring 33 having its opposite end sprung against the adjacent wall of the body whereby the two beak or bill 90 sections of the head will be normally disposed in closed position.

95 A fulcrum lever 34, mounted within the neck of the figure, has one end disposed for overlapping sliding engagement with that side of the lowermost movable bill or beak section 29 opposed to that of the spring 33. An annunciator 35 of the bulb compressed type and designed to expel a sound similar to that of the honking, hissing or quacking of 100

the particular fowl imitated, is located in the path of movement of the other end of the fulcrum lever 34. An operating shaft 36, having rigid connection with the fulcrum lever 34 at an eccentric point in the length thereof, projects outwardly through an opening in the neck of the body, forwardly and in advance of the steering shaft, and which terminates to provide a ball head or hand 10 engaging portion 37. Shifting of the shaft 36 in a downward and forward direction will cause the fulcrum lever 34 to rock upon the pivot or pivots therefor and cause the mouth and beak of the figure toy to open simultaneously with the setting of the annunciator in operation whereby the figure toy will appear more life like, that is, audibly as well as figuratively.

The invention is susceptible of various 20 changes in its form, proportions and minor details of construction and the right is herein reserved to make such changes as properly fall within the scope of the appended claim.

Having described the invention, what is 25 claimed is:

A figure wheeled toy comprising a body having a throat portion, supporting wheels for the body, means for steering and propelling the body, a lower jaw member pivoted 30 in the throat, a spring located in the throat and bearing against said member and serving to normally hold the same at a closed position, a lever fulcrumed in the throat and having one end bearing against the inner 35 end of said jaw member whereby the lever is subjected to the influence of said spring, an annunciator located in the throat and having a bulb engaged by said lever, a rod passing through the wall of the throat and 40 connected with the lever, the sound emitting end of the annunciator being disposed away from the lever and the lower jaw member.

In testimony whereof I affix my signature.
